US00D734774S

(12) **United States Design Patent**
Akana et al.

(10) **Patent No.:** US D734,774 S
(45) **Date of Patent:** ** Jul. 21, 2015

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jody Akana**, San Francisco, CA (US);
Imran Chaudhri, San Francisco, CA (US); **Jonathan P. Ive**, San Francisco, CA (US); **Christopher Wilson**, San Francisco, CA (US); **Eric Lance Wilson**, San Jose, CA (US)

(73) Assignee: **Apple Inc.**, Cupertino, CA (US)

(**) Term: **14 Years**

(21) Appl. No.: **29/457,307**

(22) Filed: **Jun. 9, 2013**

(51) LOC (10) Cl. **14-04**

(52) U.S. Cl.

USPC **D14/487**; D14/491; D14/492; D14/493

(58) **Field of Classification Search**

USPC **D14/487-495**

See application file for complete search history.

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design;

FIG. 2 is a front view of a display screen or portion thereof with graphical user interface showing our new design;

FIG. 3 is a front view of a display screen or portion thereof with graphical user interface showing our new design; and,

FIG. 4 is a front view of a display screen or portion thereof with graphical user interface showing our new design.

The broken lines around the Figures show a display screen or portion thereof with graphical user interface and form no part of the claimed design.

**1 Claim, 1 Drawing Sheet
(1 of 1 Drawing Sheet(s) Filed in Color)**
